UNITED STATES PATENT OFFICE.

ORANGE ORLANDO FELTS, OF NEW ALBANY, INDIANA, ASSIGNOR TO JOHN T. TOWSLEY, OF CINCINNATI, OHIO.

APPARATUS FOR ASSEMBLING AND GLUING UP TABLE-TOPS AND CORES FOR VENEERED WORK.

No. 926,180.

Specification of Letters Patent.

Patented June 29, 1909.

Application filed February 1, 1908. Serial No. 413,888.

To all whom it may concern:

Be it known that I, ORANGE ORLANDO FELTS, a citizen of the United States, residing at New Albany, in the county of 5 Floyd and State of Indiana, have invented certain new and useful Improvements in Apparatus for Assembling and Gluing Up Table-Tops and Cores for Veneered Work, of which the following is a specification.

10 This invention relates to wood working, and some of the objects of my improvements are, economy of labor, time, and space, simplicity of construction and operation, and to reduce the first cost of the apparatus. 15 These objects I attain by means of apparatus resembling that illustrated in the accompanying drawings, in which—

Figure 1 is a plan view of the apparatus; Fig. 2, a front elevation; Fig. 3, a plan view 20 of the clamping-table and apparatus for applying the glue to the edges of the sections of table tops and cores; Fig. 4, a side elevation of a portion of the apparatus; and, Fig. 5, a front elevation of one of the clamp-25 frames with a complete core clamped and in position for setting.

Similar reference numerals refer to similar parts throughout the several views of the drawings.

30 My improved apparatus is designed to be used in a suitable room of a building, having a floor 1 and a ceiling 2. A gluing-carriage 3, mounted upon tracks 4 and 5, a revolving glue-brush 6 mounted in a tank 7, a clamp-35 stand 8 arranged along side of tracks 4 and 5, a series of clamp-frames 9 suspended from ceiling 2 by means of trolleys 10, and an endless track 11, constitute the main features of my improved apparatus. The gluing-car-40 riage 3 comprises a U shaped frame 12, closed at the right-hand end, and without a bottom. Its sides are provided with grooved wheels 13, adapting the frame to run on the tracks 4 and 5. A movable flat clamping-bar 14 45 is joined to the near side of frame 12 by means of pivoted bars 15 and 16. A handle 17 is mounted on bar 14, preferably at the free end of bar 15. By means of bars 15 and 16, bar 14 may be moved and kept in 50 parallel relation with the near side of frame 12, so that boards 18 of the core to be glued up may be placed adjacent the far side of frame 12, and securely held together in the upright position by pushing bar 14 against

them. The right-hand ends of boards 18, 55 being placed against the right-hand end bar of frame 12, the entire lot of boards for a core may be pushed forward by pushing frame 12 by means of handle 17. Tracks 4 and 5 are mounted upon legs 19 and are 60 joined together in parallel relation with each other by means of rods 20, which at the same time form a grille bottom between the tracks. The entire track frame with its legs 19 is 65 so arranged, with the legs in sockets 21, that it may be raised from the sockets and set aside whenever access to other parts of the apparatus is required. It will be understood that when boards 18 are placed in frame 12, their lower edges rest upon rods 20. Rods 20 70 may be covered with rollers if it is desired that the boards 18 move more freely. The cylindrical glue-brush 6 mounted in its tank 7 is placed in the path of carriage 12 and is kept revolving at a suitable speed by means 75 of a belt applied to pulley 22. Carriage 12 is thus adapted to carry boards 18 over brush 6, where the lower edges of the boards are thoroughly glued, and on to the left-hand end of the track. When this has been 80 reached, a pull on handle 17 withdraws bar 14 from the boards, thus releasing them from the frame, and the frame is drawn back, leaving the boards, to the right-hand end of the track in position to be filled again. 85

One operator attends to placing the boards in frame 12, and pushing them over and delivering them upon bars 20 at the left-hand end of the track. Another operator attends to assembling the boards upon the 90 clamps which will presently be described.

The clamp-stand 8 is arranged parallel with the left-hand end of tracks 4 and 5. This clamp-stand is solidly built in order to stand considerable hammering upon the 95 boards placed thereon. It is provided with legs 23 and an upper frame 24. Above frame 24 is arranged an auxiliary movable frame 25, provided with vertically slidable posts 26, adapted to slide in frame 24 in 100 such a manner as to keep frame 25 in parallel relation with frame 24. Sets of toggles 27 are attached by one of their ends to frame 25 and by the other to a lower bar 28 of the clamp-stand. One of the sets of toggles is 105 operatively connected with a transverse rocking-bar 29, which extends forward underneath the track-stand, and is provided

at its forward end with a double treadle 30. Thus, by means of treadle 30, the auxiliary frame 25 of the clamp-stand may be raised and lowered. When the right-hand end of treadle 30 is depressed by the foot of the operator, frame 25 of the clamp-stand is raised into operative position, and when the left-hand end of treadle 30 is depressed, frame 25 is depressed and thrown out of commission. Frame 25 is provided with longitudinal angles 31, having one of their legs in a vertical plane. The vertical legs of angles 31 are suitably notched to receive clamps 32 of conventional construction. A number of clamp-frames 9 are provided and swung from the ceiling 2 of the room. The frames 9 are preferably rectangular. The square bar 33, forming the lower side of the rectangle, is pivoted in the lower ends of the frames. Clamps 32 are secured on bars 33 by means of suitable brackets in such a manner that they may be moved along bars 33, to place them at any suitable distance from each other and yet keep them in parallel relation with each other. By this means provision is made for boards of different lengths. The clamps hang vertically in frame 9, in order that they may occupy little room and the frames 9 may be placed close together (Figs. 1 and 4). Frames 9 are provided at the center of the upper side with a vertical extension. At the upper end of each vertical extension is a trolley 10 which is mounted upon a track 11, which in turn is secured to the ceiling 2 of the room, or to any suitable frame work provided therefor. The track 11 is preferably arranged in elliptical or other endless form, (Fig. 1) in order that the clamps may be filled at one end, pushed along toward the other end where the cores may be removed, and then returned to the starting place.

Frames 9 are provided on the upper bar with brackets 34 in which an extra clamp 36, to be placed on top of boards 18, is hung when the core is removed, in order that it may be easily accessible when needed for the next core. Bar 33 is provided at each end with a stop 35, rigidly secured thereto and adapted to engage an edge of the end bars of frame 9, in order to prevent clamps 32 with their core from swinging beyond the vertical plane (Fig. 4). It will thus be seen that clamps 32 may be placed horizontally upon frame 25, in order to assemble and clamp up the core, but when pushed off they may be swung into the vertical position. It will be understood that on account of stops 35, they cannot pass beyond the vertical plane, but are held in it so that they may be brought close together and a considerable number of them may occupy a small space along track 11.

The operation of the apparatus will now be understood. An operator detailed for the

work takes the boards arranged for a tabletop or a core to be veneered from a truck or other receptacle and places them vertically in proper order upon bars 20 in frame 12, as shown at 13 in Fig. 3. He then grasps handle 17, pushes bar 14 firmly against boards 18, and the carriage 12 with the boards forward over brush 6 to the left-hand end of the track in front of a second operator detailed to do the assembling and clamping up. He withdraws the carriage, leaving the boards in front of the clamp-stand 8. The operator at clamp-stand 8 draws one of the clamp frames 9 around over the clamp-stand, taking hold of the crank-handles of clamps 32 and swinging the clamps to a horizontal position over the clamp-stand. He now depresses the right-hand end of treadle 30 and thereby raises frame 25 of the clamp-stand into engagement with the suspended clamps 32, so that the clamps drop into the notches in angles 31 provided therefor and are held firmly therein. It will be understood that when the toggles of the clamp-stand are brought into vertical position, they lock frame 25 in the raised position, so that it is not necessary for the operator to keep his foot continually on treadle 30. When clamps 32 are in position he takes boards 18 from the track frame before him and places them upon the clamp in the order previously arranged. When they are all placed he screws up the clamps 32 somewhat, takes down clamp 36 from brackets 34, places it over boards 18 parallel with and between clamps 32 and then sets up all the clamps tight. If any of the boards are somewhat warped or bent, so that they do not lie within the common plane, the operator takes a hammer, which he has at hand, and knocks the high boards down to proper position. He now depresses the left-hand end of treadle 30, and thereby depresses frame 25, releasing the clamps. He seizes the crank-handles of the clamps and shoves the clamps, core and frame 9 away from him along track 11 toward the opposite end of the track. Another empty frame 9 is swung round into position and the operations just described are repeated.

The apparatus is preferably arranged in a suitable heated room adapted to dry the cores with reasonable rapidity. The track 11 is made of sufficient length to accommodate a sufficient number of frames so that when enough cores have been glued up to occupy one side of the track, those at the delivery end are sufficiently set to take down. If a hand is detailed to take down the cores at the delivery end, the operation is rendered continuous and is thus very rapidly and cheaply carried on. I contemplate raising and lowering the clamp-stand by power instead of by the treadle 30 and regard this, 130

as well as other changes in detail of construction, as within the spirit of my invention.

Having thus described my invention so 5 that any one skilled in the art pertaining thereto may make and use it, I claim—

1. Apparatus for gluing up table tops and cores for veneer work and the like, comprising a glue-tank, a rotating glue-brush mounted in said glue-tank, a track, a carriage mounted on said track for receiving boards and passing them over said glue-brush to apply the glue and deliver said boards in proper order to be assembled, and an assembling and clamping-stand positioned near said track, a trolley-track suspended from the ceiling of a room, a series of trolleys to run on said trolley-track, a series of clamp-frames suspended by said trolleys, and a set of clamps on each of said clamp-frames.

2. In apparatus for assembling and gluing up veneer-cores and table-tops and the like, means for applying glue to all the parts 25 of a core or table-top simultaneously, a carriage for handling said parts, an assembling and clamping stand adjacent to said carriage, a series of assembling and clamping-frames mounted on trolleys, and an over-head track for said clamping-frames to 30 run upon, all so arranged that an operator

may apply glue to all the parts of a veneer-core table-top and the like simultaneously and deposit them at the hand of a second operator, the second operator may assemble 35 said parts in clamps upon the assembling and clamping-stand and send the assembled and clamped articles forward toward a third operator who takes them down and returns the empty clamp frames on said over-head 40 track to the second operator, and that these operations may be repeated continuously.

3. In apparatus for assembling and gluing up veneer cores and the like, a clamp-frame comprising vertical lateral bars, a 45 horizontal bar pivoted in said lateral bars, clamps mounted on said horizontal bar at right angles thereto, and stops at the ends of said horizontal bar adapted to engage said vertical bars suitably to hold said 50 clamps in a vertical plane.

4. In apparatus for assembling and gluing up veneer-cores and other wood work, traveling and pivoted clamps, and a clamp-stand comprising a vertically movable top 55 and means to elevate and depress said movable top.

ORANGE ORLANDO FELTS.
